UNITED STATES PATENT OFFICE.

WILLIAM COPLAN, OF BALTIMORE, MARYLAND.

NECKTIE.

Application filed June 16, 1926. Serial No. 116,375.

In the manufacture of neckties as now usually fabricated the material of the tie is cut on the bias so as to provide the elasticity necessary in tying the knot. Likewise, the 5 lining for the wider or tying end of the tie is also cut on the bias for the same purpose. The lining for the narrow end of the tie is cut on the straight and the two pieces of the lining joined together at about the middle 10 of the length of the tie. Such construction, i. e., the bias cut of the wider portions of the tie and lining, is essential in order to provide a tie having the necessary tying properties, and yet the life of such a tie is greatly 15 reduced for the reason that in the tying process the pull which is repeatedly applied to the bias cut portion of the tie and lining gradually distorts this material until the tie is finally pulled out of shape and rendered 20 useless long before the material of the tie shows signs of wear. Such ties also assume a transverse curvature after being in use a comparatively short time, thus contributing to the shapelessness of the tie.

25 An object of the present invention resides in the provision of means by which the objectionable features above outlined may be obviated while retaining the elasticity due to the bias cut of the material of both the tie 30 and lining.

Another object of the invention consists in the provision of means which will function to return such a tie to its flat condition after being used, thereby eliminating the trans- 35 verse curvature usually produced in ties of this type.

Other objects and advantages of the present construction will be apparent from the following description when taken in connection 40 with the accompanying drawing; in which—

Figure 1 is a plan view of my bias cut tie turned wrong side out, the lining being omitted.

45 Figure 2 is a plan view of the lining with my improvement attached.

Figure 3 is a side elevation of the construction shown in Figure 2; and

50 Figure 4 is a plan view of a completed tie, parts being broken away to more clearly show the novel features of the construction.

Referring to the drawing in greater detail the numeral 1 indicates a necktie generally, which is composed of two pieces of bias cut material the wider or tying portion being indicated by the numeral 2 and the nar-

rower portion by the numeral 3. These portions are folded over in the usual manner into tubular form and the longitudinal edges stitched together as indicated by numeral 4. 60 These two portions of the tie are then arranged end to end and united by the seam 5.

Elasticity is not essential nor even desirable in the narrow end of a necktie, and as hereinbefore mentioned it is usual to provide 65 this end of the tie with a lining of straight cut material. Therefore, in order to reinforce this portion of the tie as well as to provide means to which the pull on the tie may be applied in the tying operation, I stitch to 70 the longitudinal seam of this end of the tie a tape of non-elastic material designated by the numeral 6. Obviously, this tape will prevent the narrow portion of the tie from 75 being pulled out of shape without in any way detracting from the material advantages of this type of tie.

The lining usually found in ties of the type to which the present invention relates consists of a wide bias cut portion 7 and a 80 relatively narrow straight cut portion 8, the two being united by a transverse line of stitching 9. As hereinbefore stated this construction alone is soon distorted by the tying operation and to obviate this disadvantage 85 which is inherent in the tie I provide a straight cut strip 10 which is attached to the lining 8 also of straight cut material by the seam 9. If desired, a loop 11 may be provided on the bias cut end of the lining and 90 the free end of the strip 10 may pass under this loop, so as to keep the strip in position with respect to the bias cut lining.

It will thus be apparent that the strip 10 is entirely free of the tie proper and that 95 any pull on the wide end of the tie will be transmitted through strip 10 to the straight cut portion of the lining 8, thereby avoiding distortion of either the bias cut lining 7 or the bias cut portion 2 of the tie.

100 The strip 10 serves another purpose in that being positioned between the lining 7 and the front or face of the tie portion 2 it acts to return the tie to flat condition after being in use; that is to say, a tie in use ordinarily assumes a slight transverse curl or bend and the strip 10 acting somewhat after the manner of a stiffener tends to remove this curl or bend and restore the tie to its normal or flat condition.

110 In the operation of tying the knot in the usual four-in-hand tie a pull must be exerted

on the larger end of the tie in order to shape the knot, and in the present construction the wearer's fingers will necessarily grip the strip 10 between the folds of the tie, and consequently the strain will be exerted upon this strip thus relieving the tie material and lining of any distorting action, yet nevertheless permitting the same freedom of movement of the parts as heretofore.

10 The tape or strip may be of any desired material and its width will vary with different ties; it being necessary only that it be of such width that it will lie between the fingers when the larger end of the tie is 15 grasped to shape the knot.

While I have particularly described my invention as applicable to bias cut ties it will be understood that the invention is by no means of such narrow scope but is adaptable 20 to ties formed of any elastic material.

In accordance with the patent statutes I have described what I now believe to be the best embodiment of the invention, but I do not wish to be understood thereby as limiting myself or the scope of the invention, as 25 many changes and modifications may be

made without departing from the spirit of the invention; all such I aim to include in the scope of the appended claims.

What I claim as new and desire to secure 30 by Letters Patent is:

1. A necktie formed of bias cut material, a lining therefor having both straight cut and bias cut portions, and a strip of straight cut material attached to the straight cut 35 portion of the lining and extending freely through the tying portion of the tie.

2. A necktie formed of bias cut material, a lining therefor having both straight cut and bias cut portions, and a strip of straight 40 cut material attached to the straight cut portion of the lining, said strip extending between the front of the tie and the bias cut portion of the lining.

3. A four-in-hand tie formed of elastic 45 material, a lining having both elastic and non-elastic portions, and a strip of non-elastic material attached to the non-elastic portion of the lining and extending freely through the tying portion of the tie.

WILLIAM COPLAN.
